UNITED STATES PATENT OFFICE

OTTO WILLIAM MATHERN, OF NEWARK, AND CLAUDE THEODORE SIEBS, OF CRANFORD, NEW JERSEY, ASSIGNEES TO WESTERN ELECTRIC COMPANY, INCORPORATED, OF NEW YORK, N. Y., A CORPORATION OF NEW YORK

ELECTRICAL SWITCHING APPARATUS

Application filed October 31, 1928. Serial No. 316,156.

This invention relates to electrical switching apparatus, and more particularly to electrical switching apparatus for use in factory testing systems.

5 In electrical testing systems frequently used in determining the characteristics of electrical apparatus such as employed in telephone exchange equipment during its manufacture, it is frequently desirable that a plurality of circuits be simultaneously disconnected in a rapid and efficient manner.

An object of the invention is to provide an electrical connection which can be easily and quickly connected with and disconnected 15 from the source of current supply.

In accordance with the general features of the invention there is provided in one embodiment thereof an electrical switching apparatus comprising a plurality of electrical 20 conducting plugs adapted to be forced into contact with conducting springs which can be simultaneously forced out of contact therewith by insulated plungers engaging the springs and operated by depressing a wall of 25 the housing in which the plungers are mounted, or by a bail connected to a common operating member for the plungers.

A clear understanding of the invention will be had from the following detailed description taken in connection with the accompanying drawings, wherein

Fig. 1 is an elevational, sectional view of an electrical plug connector and jack embodying the features of the invention;

Fig. 2 is a plan view, partially in section, of the apparatus shown in Fig. 1;

Fig. 3 is an elevational, sectional view of another form of the connector and jack, and

Fig. 4 is an end view, partly in section, of 40 the apparatus shown in Fig. 3.

Referring now to the drawings in detail in which like numerals refer to similar parts in the several figures, there is disclosed a support 10 such as a work fence to the underside 45 of which is attached a unit comprising a horizontal row of electrical connector plugs 11 electrically insulated from each other, from the left end (Fig. 1) of which project metal conducting portions 12. The support 10 has 50 attached to the left end (Fig. 1) a three-

sided metal receptacle 13 for receiving a housing 14 slideable therewithin. Inside of the housing 14 are mounted a plurality of electrical jacks 15 adapted to receive the conducting portions 12 of the plugs through apertures 18 in the right-hand end portion of the jack housing. These jacks 15 have spring connecting portions 19 which are adapted to clamp over the ends of the plugs 12, as shown in Fig. 1, for the purpose of making electrical contact therewith. Fig. 1 shows how the ends 12 of the plugs 11 may be inserted through the apertures 18 in the jack 15 so that the plug ends 12 will make electrical contact with the spring conductors 19. Through the springs 19 and metal plugs 12 any suitable multiple electrical circuit (not shown), such as one employed in testing electrical apparatus may be completed.

In order that the springs 19 may be quickly disconnected from the plugs, there are provided fibre plungers 20 which are slidably mounted within the body of the jack mounting so as to abut against the springs 19. The top of the housing 14 is made of flexible material such as sheet metal, the forward end being supported by springs 23, and by depressing the top portion and thereby compressing the springs 23 projections 24 extending from the top of the housing depress the 55 plungers 20 and force the springs 19 out of contact with the plugs 12 so that the jacks may be readily removed from contacting engagement with the plugs. When this depressing force is relieved, the housing top resumes its former position due to the springs 23, and the conducting springs 19 assume their former position in contact with the plugs 12, completing an electrical circuit connected therewith. From observing this operation it is obvious that the springs 19 may be easily and quickly disconnected from and connected with the plugs 20, since a simple depression of the top of the housing performs the purpose.

In the form of the invention shown in Figs. 3 and 4, primarily intended for use in an overhead position, there is provided a similar structure to that described above, except that the plungers 20 are depressed by a bail 25

which has its ends secured to a common strip 26 which abuts against the tops of the plungers 20. By pulling down on the bail 25 the strip 26 depresses the plungers 20 and disconnects the jacks from the plugs in the same manner as the depression of the top portion of the housing of the form shown in Figs. 1 and 2.

Thus it is seen that there is provided by this invention a jack connection with a plug which can be instantly interrupted. It is, of course, to be understood that the invention does not pertain alone to the specific disclosure thereof, but extends throughout the scope defined by the appended claims.

What is claimed is:

1. In an electrical connecting device, a housing, a plurality of jacks mounted within the housing, plugs adapted to be connected to the jacks, and means for simultaneously disconnecting the jacks from the plugs.

2. In an electrical connecting device, a housing, a plurality of jacks mounted within the housing, plugs adapted to be connected to the jacks, members for disconnecting the jacks from the plugs, and means common to the members for effecting their operation.

3. In an electrical connecting device, a housing, a plurality of jacks mounted therein in a row, plugs adapted to be connected to the jacks, each jack having a spring for making the connection and a plunger for disconnecting the spring from the jack, and means common to the plungers for effecting their operation.

4. In an electrical connecting device, a housing, a plurality of jacks mounted within the housing, and plugs adapted to be connected to the jacks, a portion of the housing being movable for disconnecting all the jacks from the plugs at one time.

5. In an electrical connecting device, a housing, a plurality of jacks mounted within the housing, plugs adapted to be connected to the jacks, a spring in each jack normally in contact with a corresponding plug, a depressible housing portion for forcing all of said springs out of contact with each of the plugs at one time, and resilient means for returning the housing portion to its normal position.

6. In an electrical connecting device, a housing, a plurality of jacks mounted within the housing, a spring in each jack adapted to receive a plug, means mounted in each jack for actuating the spring, and means common to the last mentioned means for actuating all of the springs at one time.

60 7. In an electrical connecting device, a housing, a plurality of jacks mounted within the housing, a spring connected to each jack adapted to receive a plug, a plunger mounted in each jack for actuating the spring, and a depressible member common to the

plungers for producing simultaneous operation thereof.

In witness whereof, we hereunto subscribe our names this 16th and 10th days of October, respectively, A. D. 1928.

OTTO WILLIAM MATHERN.
CLAUDE THEODORE SIEBS.
